HENRY MARTINEZ AND ROBERT HUTCHISON KIRK, OF NEWCASTLE-UPON-TYNE, ENGLAND, ASSIGNORS, BY MESNE ASSIGNMENTS, TO WINGET LIMITED, OF WARWICK, ENGLAND, A CORPORATION OF GREAT BRITAIN AND NORTHERN IRELAND

MACHINE FOR CRUSHING COAL, STONE, AND SIMILAR MATERIALS

Application filed May 14, 1930, Serial No. 452,316, and in Great Britain May 21, 1929.

This invention relates to machines for crushing coal, stone and similar materials, and has for its object to provide an improved machine. The machine of the present invention has been especially designed for use in places where both the inlet and the outlet from the machine are liable to become choked; for example, where the crushing machine is interposed between an outlet from a ship's bunkers and the feed hopper of a coal pulverizer feeding the boiler furnaces to ensure that none of the pieces of coal fed to the pulverizer exceed a certain size.

In a crushing machine in accordance with the present invention, the opposed members between which the material is crushed are so mounted that, in case of choking or fouling, abnormal resistance is absorbed by resilient devices, and are characterized in that said resilient devices are positioned so as to allow said members to yield at both the intake and the output end of the machine. The operative member normally has imparted to it an oscillatory movement, and the material is crushed between it and an abutment, but, if desired, a second operating member may be substituted for the abutment. The crushing power is normally transmitted to the operative members through resilient devices which absorb said power when the resistance of the material between the crushing members exceeds the normal, and the relative movement between the crushing members changes from a crushing motion to a rubbing or rolling motion, the crushing motion being absorbed by the resilient mountings which are preferably adjustable to vary their resistance. The machine is thus adapted to deal, without choking or risk of damage to its parts, with materials fed to it in varying quantities and without control, and is particularly suitable for dealing with crushable materials such as coal, coke and the like with which uncrushable materials such as iron, wood or the like may be mixed.

Usually the abutment of the machine is stationary, the coating member being resiliently actuated, but the abutment may be resil-

iently mounted and the coating member positively operated.

We will more fully describe our invention with reference to the accompanying drawings which illustrate crushing machines in accordance therewith. In the drawings, Figure 1 is an elevation of one construction, the nearer side plate being removed for clearness, and Figure 2 is a plan thereof; Figure 3 is a similar view of Figure 1 illustrating a modified construction; Figure 4 is a similar view to Fig. 1 illustrating a further modification, and Figure 5 is an end elevation of the machine shown in Fig. 4.

Referring to the said drawings, in the example illustrated in Figs. 1 and 2, the crushing machine comprises a casing having an end wall 10 forming a strong abutment against which the coal or other material is crushed. The operative members comprise two sets of toothed wheels 11, 12 spaced on a pair of parallel horizontal transverse shafts 13, 14, the wheels of one set entering the spaces between the wheels of the other set. One set of operative members is disposed below and nearer to the abutment 10 than the other. The lower shaft 13 is supported in resiliently-mounted bearings 15 on the side plates 16 of the machine, and the upper shaft 14 is carried by arms 17 on said lower shaft so as to be capable of oscillating to a limited degree thereabout. The shafts 13, 14 are fitted with cranks 18, 19, the lower cranks 19 being linked to the upper cranks by links 20, and the upper cranks 18 being pivoted at 21 to crossheads 22 on rods 23 attached to sheaves 24 embracing eccentrics 25 on a suitably supported and driven rotary shaft 26. Each crosshead 22 lies between a pair of springs 27, 28 mounted on the eccentric rod 23, said springs normally holding said crosshead in mid-position so that it reciprocates with the eccentric rod, the reciprocations of the crossheads being simultaneously transmitted to the two sets of operative members 11, 12 by the coupled cranks 18, 19. A third spring 29 is disposed at an oblique angle to each eccentric rod 23 on the opposite side of the crosshead 22 to the operative members, said spring

being mounted about a pin 30 pivoted at one end to the crosshead and at the other end sliding through a pivoted block 31 mounted on the adjacent side plate 16 of the machine, this arrangement imparting to the upper operative member 11 an oscillatory movement about the shaft 14 of the lower crushing member.

Should abnormal obstruction occur between the crushing members 11, 12 and the abutment 10 due to choking of the intake end or of the output end of the machine, or both, the oscillatory movement of the upper operative member 11 about the lower shaft 14 stops and the oscillation of the crossheads 22 is transferred to the oblique pins 30 and absorbed by their springs 29, both operative members continuing to oscillate about their own axes. Should a piece of metal or other comparatively unbreakable substance become wedged between the operative members and the abutment, or should the density of the choke become such as to prevent any movement of the operative members, the motion of these members stops and the eccentric rods 23 reciprocate through the crossheads 22, the power which is normally transmitted by the crossheads to the crushing members being absorbed by the springs 27, 28.

30 The springs 27, 28 and 29 are adjustable as to tension by adjusting the nuts 32 on the rods 23 or the nuts 33 on the pins 30.

In the machine illustrated in Fig. 3, a jaw 34 is substituted for the crushing wheels 11, 35 12 of Figs. 1 and 2, and the upper end of this operative jaw 34 is pivotally connected by a link 35 to an adjustable block 36 on the eccentric rod 23 carried by the sheave 24 of the eccentric 25 on the driving shaft 26 of the machine, and the lower end of the jaw 34 is pivotally attached at 40 to one arm 37 of a cranked lever, the fulcrum 38^a of which may be fixed or adjustable or may slide against the resistance of suitable springs, the other 45 arm 38 of said cranked lever being connected by a link 39 to the crosshead 22 on the eccentric rod 23, said crosshead being adjustably disposed between the block 36 and the eccentric 25. The springs 27 and 28 of Figs. 1 and 2 are dispensed with. Opposing the upper link 35 is the oblique pin 30 sliding through a hole in the pivoting block 31 as in Figs. 1 and 2. The adjustable spring 29 is disposed about the pin 30 between the blocks 50 36 and 31. The attachment between the lower end of the jaw 34 and the cranked lever 37, 38 may be resilient in the direction between the point of attachment 40 to the jaw and the fulcrum 38^a of said lever but not laterally, 55 or the connection between the cranked lever 37, 38 and the link 39 connecting it to the crosshead 22 may be resilient. The abutment 10 of the machine is stationary, and the mechanism is duplicated at each side of the machine and carried by the side plates 16 be-

tween which the abutment 10 and jaw 34 are mounted as illustrated in Figs. 1 and 2.

Normally, a substantially oscillatory motion is imparted to the operative jaw 34 by the block 36 on the eccentric rod operating through the upper link 35 and by the crosshead 22 operating through the lower link 39 and cranked lever 37, 38. Should the machine become choked or a piece of unusually hard material come between the abutment 10 and the jaw 34, the crushing action of the jaw becomes a rubbing or rolling motion tending to pass the congregated material or uncrushable piece down between the jaw and the abutment, the crushing power being transferred to the spring 29 opposed to the link 35 and to the resilient connections between the cranked lever 37, 38 and the lower end of said jaw or the link 39, where such connections are fitted. The jaw 34 thus "marks time" until the stoppage or obstruction is cleared.

In the modified construction illustrated in Figs. 4 and 5, the upper end of the operative jaw 34 is pivoted at 41 to the centre of a crosshead 42 provided with rods 43 sliding through a block 44 connected to the sheaves 24 of a pair of eccentrics 25 on the driving shaft 26, springs 27, 28 being disposed around the rods 43 between the crosshead 42 and the block 44 and between the latter and adjustable stops 45 on the ends of the rods, the arrangement allowing the upper end of the jaw 34, when it meets abnormal resistance, to move towards the driving shaft 26 against the resistance of the springs 27, 28 but not laterally. The lower end of the operative jaw 34 is adjustably connected by a link 46 to a lug 47 on the eccentric sheave 24, and its movement away from the abutment 10 is opposed by the spring 29 about the pin 30 which slides through a hole in the pivoted block 31 which forms a resilient anchorage. This construction may be further modified by dispensing with the adjustable links 46, the lower end of the jaw 34 being directly pivoted to the spring enclosed pin 30. Also, where a wider jaw 34 is provided, the eccentrics 25, blocks 44, crossheads 42 and associated parts and the link 46, pin 30 and block 31 may be duplicated or triplicated as may be required to ensure proper actuation of the jaw.

It will be seen that the output at the lower end of the operative jaw 34 can be varied from nothing to a maximum by varying the angle of the pivoted pin 30 to the jaw; for example, by shortening the link 46 by means of the coupling 48, the lug 40 by which the link and the pin 30 are attached to the jaw can be raised and the to-and-fro movement of the lower end of the jaw about the pivoted block 31 increased, while, by lengthening said link, said to-and-fro movement can be decreased to zero. The same effect is obtained by raising or lowering the pivoted block 31 or the

pivot 38 of Fig. 3. Simple and effective means are thus provided whereby the feed of the crushing machine can be varied according to requirements.

5 In all the above arrangements, the springs absorbing abnormal resistance to the operative jaw 34 may be dispensed with and the stationary jaw 10 resiliently mounted so that it floats and gives when the machine becomes 10 choked or when an abnormally hard obstruction comes between the jaws, movement of said floating jaw 10 in vertical directions being prevented by guides or otherwise suitably thus restricting the floating jaw to movements 15 towards and away from the operative jaw 34.

Alternatively, we may, if desired, substitute for the abutment 10 a second operative member or jaw similar to but opposed to the jaw 20 34 of the constructions illustrated in the drawings, the actuating mechanism of the second jaw being simultaneously operated with that of the first jaw through suitable gearing.

25 What we claim as our invention, and desire to secure by Letters Patent is:—

1. A machine for crushing coal, stone and similar materials comprising a casing, opposed crushing members mounted in said casing, one of said crushing members being a floating operative member, bearings carried by said casing, a rotary driving shaft mounted in said bearings, oscillatory mechanism on said shaft, a connection between said oscillatory mechanism and said operative crushing member, an anchorage in said casing, and a resilient device interposed between said connection and said anchorage and absorbing the drive to the intake end of said operative crushing member when it meets abnormal resistance.

2. A machine for crushing coal, stone and similar materials comprising a casing, opposed crushing members mounted in said casing, one of said crushing members being a floating operative member, bearings carried by said casing, a rotary driving shaft mounted in said bearings, oscillatory mechanism on said shaft, a connection between said oscillatory mechanism and said operative crushing member, an anchorage in said casing, and a resilient device interposed between said connection and said anchorage and absorbing the drive to both the intake and the output ends of said operative crushing member when it meets abnormal resistance.

3. A machine for crushing coal, stone and similar materials comprising a casing, opposed crushing members mounted in said casing, one of said crushing members being a floating operative member, bearings carried by said casing, a rotary driving shaft mounted in said bearings, oscillatory mechanism on said shaft, a connection between said oscillatory mechanism and said operative

crushing member, an anchorage in said casing, a resilient device interposed between said connection and said anchorage and absorbing the drive to both the intake and the output ends of said operative crushing member when it meets abnormal resistance and resilient devices inserted between said oscillating mechanism and said connection through which the power for actuating the operative crushing member is transmitted.

4. A machine for crushing coal, stone and similar materials comprising a casing, opposed crushing members mounted in said casing, one of said crushing members being a floating operative member, bearings carried by said casing, a rotary driving shaft mounted in said bearings, oscillatory mechanism on said shaft, a connection between said oscillatory mechanism and said operative crushing member, an anchorage in said casing, a resilient device interposed between said connection and said anchorage and absorbing the drive to both the intake and the output ends of said operative crushing member when it meets abnormal resistance, resilient devices inserted between said oscillating mechanism and said connection through which the power for actuating the operative crushing member is transmitted and means for adjusting the gap at the output end of the crushing members to vary the output of the machine.

5. A machine for crushing coal, stone and similar materials comprising a casing, opposed crushing members mounted in said casing, one of said crushing members being a floating operative member, bearings carried by said casing, a rotary driving shaft mounted in said bearings, oscillatory mechanism on said shaft, a connection between said oscillatory mechanism and said operative crushing member, an anchorage in said casing, a resilient device interposed between said connection and said anchorage and absorbing the drive to both the intake and the output ends of said operative crushing member when it meets abnormal resistance, resilient devices inserted between said oscillating mechanism and said connection through which the power for actuating the operative crushing member is transmitted and means for adjusting the gap at the output end of the crushing members to vary the output of the machine, said oscillatory mechanism comprising an eccentric on said driving shaft, a spring-loaded crosshead, and an operative connection between said eccentric and said crosshead.

6. A machine for crushing coal, stone and similar materials comprising a casing, opposed crushing members mounted in said casing, one of said crushing members being a floating operative member, bearings carried by said casing, a rotary driving shaft mounted in said bearings, oscillatory mechanism on said shaft, a connection between said oscillatory mechanism and said operative
